CLAIM

The ornamental design for removable support mount part as shown and described.

DESCRIPTION

FIG. 1 is a top perspective view of a removable support mount part in accordance with my new design;
 FIG. 2 is a bottom perspective view of the removable support mount part of FIG. 1;
 FIG. 3 is a top view of the removable support mount part of FIG. 1;
 FIG. 4 is a bottom view of the removable support mount part of FIG. 1;
 FIG. 5 is a right-side elevation view of the removable support mount part of FIG. 1;
 FIG. 6 is a left-side elevation view of the removable support mount part of FIG. 1;
 FIG. 7 is a front elevation view of the removable support mount part of FIG. 1; and,
 FIG. 8 is a rear elevation view of the removable support mount part of FIG. 1.
 The broken lines in the drawings illustrate portions of the removable support mount part that form no part of the claimed design.
